UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-CARS.

SPECIFICATION forming part of Letters Patent No. 792,229, dated June 13, 1905.

Application filed February 17, 1905. Serial No. 245,995.

To all whom it may concern:

Be it known that I, WILLIAM H. MINER, a citizen of the United States, residing in Chicago, in the county of Cook and State of Illinois, have invented a new and useful Improvement 5 in Draft-Rigging for Railway-Cars, of which the following is a specification.

My invention relates to improvements in draft-rigging for railway-cars, and more particularly to tandem-spring draft-rigging.

My invention consists in the novel construction of parts and devices and in the novel combinations of parts and devices herein shown and described, and specified in the 15 claims.

In the accompanying drawings, forming a part of this specification, Figure 1 is a side elevation, partly in vertical longitudinal section, of a tandem-spring draft-rigging embodying my invention. Fig. 2 is a plan view, partly in horizontal section. Fig. 3 is a vertical cross-section on line 3-3 of Fig. 2. Fig. 4 is a perspective view of the filler and tie casting bar or block, and Fig. 5 is a perspective view of the lower removable guide and connecting plate.

In the drawings, A A represent the longitudinal center sills of the car-frame; A', the front sill; A², the draft-timbers; A³, the buffer-block, and A⁴ the carry-iron.

B is the coupler, B' the draw-bar, B² the draw-bar extension, the same being preferably in the form of a yoke or strap and secured to the draw-bar by bolts b. The draw-bar and draw-bar extension have shoulders or abutments b' b² b³ to bear against the followers C.

E E are tandem-arranged springs interposed between each pair of followers C, there 40 also being preferably smaller springs e e inside the larger springs E.

D D are the side plates or stop-castings, the same having shoulders or stops d d' d² for the followers C to abut against and each having 45 an upper integral guide or flange d³ for the followers. Each of the side plates or stop-castings D is also provided with an external horizontal flange d⁴ to fit under the draft-timbers A² and through which flanges d⁴ up-

right bolts d⁵ pass to secure the side plates or 50 stop-castings D to the draft-timbers and center sills. Horizontal bolts d⁶ also extend through the draft-timbers and the side plates or stop-castings to further secure the same in place. Each of the side plates or stop-castings D is further provided with an extension D' at its front end, which extends to the front 55 of the car and projects under the front sill A' and buffer-block A³ and the bottom plate A⁵ of the buffer-block. This extension D' of the 60 side plate or stop-casting D is provided with a shoulder d⁷ to accommodate the bottom plate A⁵ of the buffer-block and with an integral projection d⁸ on its upper side, having a shoulder d⁹ to fit and bear against the rear 65 face of the front or cross sill A' and furnished with a recess d¹⁰ to receive the filler and tie casting block or bar F, the projection d⁸ having also a shoulder d¹¹ to abut against said filler and tie casting F. The center sill A is 70 notched or recessed to receive the projection d⁸ and the filler and tie casting F. Upright bolts d¹² extend through the buffer-block and carry-iron and the front ends of the side-plate or stop-casting extensions D'. Similar up- 75 right bolts d¹⁴ extend through the front sill A' and these extensions D' of the side plates or stop-castings D, and upright bolts d¹⁵ extend through the filler and tie casting F and side plates D.

G is the lower guide and connecting plate, the same being removably secured to the side plates D by short bolts g, which extend through the lower horizontal flanges d¹⁶, with which the side plates D are provided. This 85 plate G serves as a lower guide for the followers and also as a connecting-plate for the two side plates or stop-castings D D. The plate G is provided with marginal flanges g', which embrace the outer edges of the stop-cast- 90 ing flanges d¹⁶. This guide and connecting plate G is further provided with downwardly-projecting flanges g², forming a channel and guide g³ for the draw-bar extension B².

The extensions D' of the side plates or stop- 95 castings D have shoulders d¹⁷, which receive and abut against the front ends of the draft-timbers A², and also laterally-projecting

brackets d^{18} to receive the truss-rods H, which are thus connected directly to the side-plate or stop-casting extensions, thus affording a further and additional anchorage for the side 5 plates or stop-castings. By this construction the side plates or stop-castings are very firmly and rigidly secured and anchored to the car-framework both against pulling and buffing strains, and the draft-rigging as a whole is 10 rendered very strong, safe, and reliable.

I claim—

1. In a draft-rigging, the combination with the draw-bar, draw-bar extension, tandem springs and followers, of the center sills, draft-timbers, cross-sill and buffer-block and a pair of side plates or stop-castings, each having stops for the followers to abut against, and provided each with an extension at its front end extending under the cross-sill, a buffer-block, upright bolts extending through said draw-bar extensions and the front sill and buffer-block, each of said side plates or stop-castings having on its upper side a projection furnished with a shoulder abutting against 25 the rear face of the front or cross sill, and said projection having a shouldered recess to receive a filler and tie casting, a filler and tie casting fitting in said shouldered recess and connecting said side plates or stop-castings, 30 and a lower removable guide and connecting plate removably secured to and connecting the side plates or stop-castings, substantially as specified.

2. In a draft-rigging for railway-cars, the 35 combination with a pair of side plates or stop-castings furnished each on its upper side with a projection having a shouldered recess, of a filler and tie casting fitting in said shouldered recess and extending across and connecting 40 said side plates or stop-castings, substantially as specified.

3. In a draft-rigging for railway-cars, the 45 combination with the draft-timbers and front or cross sill, of side plates or stop-castings furnished each with an extension extending under and bolted to the cross-sill, and provided each on its upper face with a shouldered projection and a filler and tie casting or bar fitting in said shouldered recesses and extend-

ing across and connecting the side plates or 50 stop-castings, substantially as specified.

4. In a draft-rigging for railway-cars, the combination with the draft-timbers and front or cross sill, of side plates or stop-castings furnished each with an extension extending 55 under and bolted to the cross-sill, and provided each on its upper face with a shouldered projection and a filler and tie casting or bar fitting in said shouldered recesses and extending across and connecting the side plates or 60 stop-castings, said extensions of the side plates or stop-castings having lateral flanges or shoulders to receive the tie-rods, and tie-rods connected thereto, substantially as specified.

5. In a draft-rigging for railway-cars, the 65 combination with the center sills, of side plates or stop-castings each furnished with a shouldered projection on its upper side, said center sills having shouldered recesses to receive and bear against said shouldered projections on 70 the upper side of the side plates or stop-castings, said shouldered projections on the upper side of the side plates or stop-castings having shouldered recesses to receive the filler and tie casting, and a filler and tie casting fitting 75 in said recesses and extending across and connecting said side plates or stop-castings, substantially as specified.

6. In a draft-rigging for railway-cars, the combination with the center sills, of side plates 80 or stop-castings each furnished with a shouldered projection on its upper side, said center sills having shouldered recesses to receive and bear against said shouldered projections on 85 the upper side of the side plates or stop-castings, said shouldered projections on the upper side of the side plates or stop-castings having shouldered recesses to receive the filler and tie casting, and a filler and tie casting fitting 90 in said recesses and extending across and connecting said side plates or stop-castings, and a front or cross sill abutting directly against said filler and tie casting, substantially as specified.

WILLIAM H. MINER.
